UNITED STATES PATENT OFFICE.

SOLOMON CAHAN, OF NEW YORK, N. Y.

METAL MATTRESS FABRIC FOR BEDS.

Application filed December 19, 1922. Serial No. 607,838.

To all whom it may concern:

Be it known that I, SOLOMON CAHAN, a citizen of the United States, residing in New York, in the county of New York and State of New York, have invented certain new and useful Improvements in Metal Mattress Fabrics for Beds, of which the following is a specification.

The present invention relates to spring fabrics for reclining or sitting thereon such as beds, couches and the like, and one object of the invention is to provide a spring fabric of links of dual wires, the fabric having resiliency throughout the entire plane thereof and being free from the tendency to form therein permanent depressions or pockets due to weight habitually imposed thereon.

Another object is to provide a spring fabric in which the strain due to the weight imposed thereon is distributed over links composed of dual wires or strands, the links coacting to yieldably sustain the strain placed upon the fabric.

Another object is to provide a spring fabric comprising links composed of dual wires or strands, the links being connected laterally to each other by overlying and underlying engagement for forming the fabric and coacting with each other to yieldably sustain the weight imposed thereon.

Another object is to provide a spring fabric comprising links, each link consisting of an outer or enclosing wire or strand and an inner or enclosed wire or strand which conformably engages the outer wire or strand in the same plane and coacts therewith to form the link.

I attain these and such other objects and advantages as may appear during the subjoined description by way of example of one embodiment of the invention, shown in the accompanying drawings in which Figure 1, is a plan view, the spring fabric being broken transversely and longitudinally for convenience of illustration and indicating that it is composed in width and length of a greater number of links than shown in said view.

Figure 2, is a fragmentary plan view of the spring fabric shown in Fig. 1, provided with a modified form of marginal connection, the spring fabric being broken transversely.

Figure 3, is a sectional view of the spring fabric on the line 3—3 of Fig. 1, looking in

the direction of the adjacent section arrows of Fig. 1, the spring fabric being broken transversely.

Figure 4, is a sectional view of the spring fabric on the line 4—4 of Fig. 2, looking in the direction of the adjacent section arrows of Fig. 2, the spring fabric being broken transversely.

Figure 5, is a sectional view on the line 5—5 of Fig. 1, looking in the direction of the adjacent arrows of Fig. 1, the spring fabric being broken longitudinally.

Figure 6, is a fragmentary sectional view on the line 6—6 of Fig. 2, looking in the direction of the adjacent section arrows of Fig. 2.

Figure 7, is a fragmentary sectional view on the line 7—7 of Fig. 2, looking in the direction of the adjacent section arrows of Fig. 2.

Figure 8, is a fragmentary detail view on an enlarged scale of interlocked or overlapped links, showing the manner of connecting the links laterally.

Figure 9, is a fragmentary detail view on an enlarged scale of fabric links connected at ends of the links, and

Figure 10, is a fragmentary detail view on an enlarged scale of one end of a fabric link and a helix connecting member showing the manner of connecting the links at one of their ends to the helix members.

Similar reference characters denote similar parts throughout the several views.

The spring fabric is shown in connection with a frame having end-pieces 10 and 11 and side-pieces 12 and 13, but it should be understood that I do not restrict myself to a frame of any particular form or construction.

The spring fabric comprises in its main parts or elements the mid-links 14, marginal links 15 and helix connecting members 16.

The end-pieces 10 and 11 have therethrough the spaced holes 18 for receiving hooked ends of the helix members 16 later described. The mid-links 14 are substantially diamond shape, having at one end the eyes 19 and at the opposite end the hooks 20, the eyes 19 lying in one plane, as shown in a horizontal plane, and the hooks 20 lying in a transverse plane, as shown in a vertical plane. Each of the mid-links 14 consists of dual wires or strands bent into conforming engagement on the same plane whereby an outer or enclosing link and an inner or en-

closed link is formed, both of the outer and inner links lying on substantially the same plane, and constituting a link of dual wires having the eye portion 19, and the hook 5 ends 20 formed at the free ends of the dual wires, the hook ends 20 having four hooked portions. The opening of the eye 19 is of such size and curvature as to receive the quadruple hook portions of the hook ends 10 20 of another link and prevent movement of the hook ends in the eye, and maintain the dual wires composing the hook ends 20 of the second link in the horizontal plane of these dual wires in the body of such link. 15 For operatively connecting laterally a mid-link 14 to an adjacent mid-link 14, the side of the first link at the obtuse portion of the diamond adjacent to the corresponding obtuse portion of 20 a second mid-link is carried over and then under the second link, as shown in Fig. 8, whereby the mid-links cooperate for supporting each other, the dual wires or strands of one link bearing down upon and then up- 25 wardly upon the dual wires or strands of the other link. For connecting the mid-links 14 to each other longitudinally, the hook end 20 of one link is engaged in the eye 19 of a second link as shown in Fig. 9, the eyes 30 19 of the mid-links preventing movement of the quadruple wires or strands of the hook ends 20 in the eyes, and maintaining the dual wires or strands composing the hook ends in substantially the plane occupied by these 35 wires in the bodies of the links.

For connecting the mid-links 14 to end-pieces such as 10 and 11, the helix members 40 16 are provided. The helix members 16 have helix body portions having at one end a hook 21 with an indentation or pocket 22 formed thereon, and having at their other end a circular hook 23. For connecting the mid-links 14 to the end-pieces 10 the eyes 19 of the mid-links are engaged in the indentations or pockets 22 of the helix members, 45 these indentations or pockets preventing movement of the dual wires or strands of the eyes 19 of the mid-links out of the same plane, the circular hooked ends 23 of the helix members being engaged in the spaced holes 18 of the end-pieces 10. For connecting the mid-links 14 to the end-piece 11, the rings 24 are provided, having somewhat elongated openings 25 of a size and shape to 50 receive the hook ends 20 of the mid-links, and serving to prevent movement of the hook ends and to maintain the wires or strands of the mid-links and of the hook ends 20 in the same plane, the circular hooks 55 23 of the helix members being engaged in the spaced holes 18 of the end-piece 11.

The marginal links 15 are substantially one-half portions of the mid-links 14, the mid-links being cut longitudinally. The 60 marginal links 15 like the mid-links 14 are

composed of dual wires or strands, and have eyes 26 and hooked ends 27 similar to the eyes 19 and hooked ends 20 of the mid-links, but have straight sides and two inclined sides connected by obtuse portions of the links. The marginal links 15 are connected to each other by engagement of the hooked ends 27 in the eyes 26 in manner similar to that before described for connecting the mid-links to each other, and are connected to the end-piece 10 by the eyes 26 engaging with the indented ends 21 of helix members 16, the circular ends 23 whereof engage the spaced holes 18 of the end-piece 10, and are connected to the end-piece 11 by the hooked ends 27 engaging in the rings 20 which are connected to the helix members 16 having their circular ends 23 engaging in the spaced holes 18 of the end-piece 11. The obtuse side portions of the marginal links 15 are connected to obtuse side portions of adjacent mid-links 14 by the same manner of overlying and underlying engagement as before described for connecting the mid-links 14 to each other laterally or at their sides. 70 75 80 85 90 95

It will be noted that the marginal links 15 constitute means for supporting the mid-links 14 in the longitudinal line of the spring fabric at the margins of the mid-portion of the spring fabric formed by the mid-links.

Instead of the marginal links 15 marginal plates 28, Fig. 2, may be used. The marginal plates 28 extend longitudinally of the spring fabric, being connected at respective 100 ends to the end-pieces 10 and 11 by helix members 16 engaging in the holes 18 in the end-pieces. The marginal plates are provided with longitudinally alined openings, such as 29 and 30, therethrough near their inner edges, these edges being rolled or channeled and provided with substantially circumflex raised and depressed portions 31 and 32, shown in Fig. 7, for receiving the wires or strands of the mid-links 14, the obtuse portions of adjacent mid-links being received in the openings 29 and 30 in overlying and underlying engagement for supporting the mid-links in the longitudinal line of the spring fabric at the margins of the mid-portion thereof formed by the mid-links. 110 115

Having thus described my invention, it should be understood that there may be modifications thereof and variations therein without departing from the spirit of the invention or exceeding the scope of the appended claims. 120

What I claim and desire to protect by Letters Patent is:

1. In a spring fabric, the combination of, 125 mid-links operatively connected to each other for providing the mid portion of the fabric; and marginal plates having alined openings in one of the edges thereof for overlying and underlying engagement of the 130

plates with mid-links composing the mid portions of the fabric for supporting the mid-links at the margins of the fabric.

2. In a spring fabric, the combination of, 5 mid-links operatively connected to each other for providing the mid portion of the fabric; and marginal plates having one of the edges thereof rolled and having alined openings therein with raised and depressed portions of the edges adjacent to the openings, for connection of the plates by overlying and underlying engagement of the plates with mid-links composing the mid portion of the fabric for supporting the 10 mid-links at the margins of the fabric.

3. In a spring fabric, the combination of, 15 a frame having side portions and end portions; a fabric comprising mid-links having terminal eyes and terminal hooks and composed of dual wires conformably engaging each other on the same plane; the body portions of the mid-links having extended side portions; the mid-links being connected to each other at adjacent side portions by overlying and underlying interlocking engagement with each other and being connected to each other at their ends by engagement of the terminal hooks with the terminal eyes of adjacent mid-links; means for resiliently 20 connecting to one of the end portions of the frame the terminal eyes of mid-links adjacent to said end portion; said means being adapted to prevent movement of the terminal eyes when engaged therewith and to 25 maintain the wires composing the eyes in the plane occupied by said wires in the body portions of the mid-links; means for resiliently connecting to the opposite end portion of the frame the terminal hooks of mid-links adjacent to said end portion; said means being adapted to prevent movement of the terminal hooks when engaged therewith and to maintain the wires composing the hooks in the plane occupied by said wires 30 in the body portions of the links; and marginal plates connected at their ends to end portions of the frame and connected by overlying and underlying interlocking engagement with the side portions of mid-links adjacent to the plates for supporting the mid-links at the outer sides thereof.

25 4. In a spring fabric, the combination of, 20 a frame having side portions and end portions; mid-links connected to each other and connected to end portions of the frame, the mid-links having extended side portions; and plates connected to end portions of the frame and having in one edge alined spaced openings; the plates being connected to adjacent side portions of mid-links by overlying and underlying engagement of said side portions with said 25 openings for providing support for the mid-links at the outer sides thereof.

30 5. In a spring fabric, the combination of, 35 a frame having side portions and end portions; mid-links connected to each other and connected to end portions of the frame, the mid-links having extended side portions and being composed of dual wires conformably engaging each other on the same plane; and plates connected to end portions of the frame and having a rolled edge with alined spaced openings therein and a depressed and raised portion of the rolled edge on each side of the openings and adjacent thereto; the plates being connected to adjacent side portions of mid-links by overlying and underlying engagement of said side portions with said 40 openings and depressed and raised portions of the plates for providing support for the mid-links at the outer sides thereof.

35 6. In a spring fabric, the combination of, 45 a frame having side portions and end portions; a fabric comprising mid-links having terminal eyes and terminal hooks and composed of dual wires conformably engaging each other on the same plane; the body portions of the mid-links having extended side portions; the mid-links being connected to each other at adjacent side portions by overlying and underlying interlocking engagement with each other and being connected to each other at their ends by engagement of the terminal hooks with terminal eyes of adjacent mid-links; means for resiliently con-

necting to one of the end portions of the frame the terminal eyes of mid-links adjacent to said end portions; said means being adapted to prevent movement of the terminal eyes when engaged therewith and to maintain the wires composing the eyes in the plane occupied by said wires in the body portions of the mid-links; means for resiliently connecting to the opposite end portion of the frame the terminal hooks of mid-links adjacent to said end portion; said means being adapted to prevent movement of the terminal hooks when engaged therewith and to maintain the wires composing the hooks in the plane occupied by said wires in the body portions of the links; and marginal plates connected at their ends to end portions of the frame and connected by overlying and underlying interlocking engagement with the side portions of mid-links adjacent to the plates for supporting the mid-links at the outer sides thereof.

5. In a spring fabric, a frame having side portions and end portions; mid-links connected to each other and connected to end portions of the frame, the mid-links having extended side portions; and plates connected to end portions of the frame and having in one edge alined spaced openings; the plates being connected to adjacent side portions of mid-links by overlying and underlying engagement of said side portions with said openings for providing support for the mid-links at the outer sides thereof.

6. In a spring fabric, a frame having side portions and end portions; mid-links connected to each other and connected to the end portions of the frame, the mid-links having extended side portions and being composed of dual wires conformably engaging each other on the same plane; and plates connected to end portions of the frame and having a rolled edge with alined spaced openings therein and a depressed and raised portion of the rolled edge on each side of the openings and adjacent thereto; the plates being connected to adjacent side portions of mid-links by overlying and underlying engagement of said side portions with said openings and depressed and raised portions of the plates for providing support for the mid-links at the outer sides thereof.

7. In a spring fabric of the character described, the combination of, links having terminal eyes and terminal hooks and composed of dual wires conformably engaging each other on the same plane; and helix members having indented hooked portions to receive the terminal eyes or terminal hooks of the links and prevent movement of the eyes or hooks when engaged therewith and to maintain the wires composing the eyes or hooks in the plane occupied by said wires in the body portions of the links.

SOLOMON CAHAN.
